Hamlin J. Lloyd
By his Attorney, Ged. S. Myers

UNITED STATES PATENT OFFICE.

HAMLIN J. LLOYD, OF WYALUSING, PENNSYLVANIA.

VIGNETTER.

SPECIFICATION forming part of Letters Patent No. 425,812, dated April 15, 1890.

Application filed May 15, 1888. Serial No. 274,011. (No model.)

To all whom it may concern:

Be it known that I, HAMLIN J. LLOYD, a citizen of the United States, residing at Wyalusing, in the county of Bradford and State 5 of Pennsylvania, have invented certain new and useful Improvements in Vignettters; and I do declare the following to be a full, clear, and exact description of the invention, such as will enable others skilled in the art to 10 which it appertains to make and use the same, reference being had to the accompanying drawings, and to the letters of reference marked thereon, which form a part of this specification.

15 My invention relates to improvements in photography; and it consists of devices by which an operator is enabled to vignette the negative in the camera during exposure in such a manner as to produce a variety of 20 differently-shaded vignettes, varying in any degree between black and white. This result I accomplish by suspending variously-shaded vignette boards or plates in front of the lens during exposure, thereby vignetting the neg- 25 ative in the camera-box of a shade corresponding to the shading on the vignette-board.

In the drawings similar letters refer to similar parts throughout.

Figure 1 is a view of a portion of a camera- 30 box and lens with an arm attached thereto carrying a frame in which the vignette board or plate is suspended. Fig. 2 shows the arm and frame detached with a vignette-board in place. Figs. 3 and 4 represent two differently- 35 shaded vignette boards or plates, illustrating the manner in which I prepare vignette boards or plates to produce in the camera during exposure a great variety of gradually- shaded negatives. Fig. 5 is an enlarged de- 40 tail view.

A is a set-screw passing through slot S for attaching the arm C to the camera-box M, by means of which the attachment is easily fastened to or removed from the box M.

45 D is the frame in which the vignette-board is suspended, and K its arm or handle.

C represents an arm extending from the camera-box.

B is a set-screw, G its washer, and E its 50 nut, by means of which the frame D is held to and adjusted in the arm.

The arm C is slotted both perpendicularly and horizontally, the perpendicular slot extending to the outer end of the arm, and the horizontal slot being closed at the outer end 55 and provided with a square-cut groove g on one side along the slot S, adapted to receive the nut E and prevent its turning with set-screw B. When the screw is loosened, the nut slides along the groove g as the set-screw 60 is moved back and forth along the slot S, carrying with it the frame D. Through the perpendicular slot P the frame D is suspended by its arm or handle K, and is held in place and adjusted in the desired position as to 65 height, distance from, and inclination to the lens L by the set-screw B. By the slot P being cut through to the end of the arm C sufficient elasticity is given to the sides of the arm to allow them to press arm K and hold 70 frame D in position by tightening set-screw B.

F, H, and J represent thin plates, of cardboard, metal, wood, or other suitable material, provided with central openings I to admit rays of light from the object being photographed. 75 By suspending one of these boards or plates in front of the camera with its colored or shaded side facing the lens the negative in the camera is vignetted a graduated shade.

A great variety of differently - shaded 80 vignettes can thus be produced by differently-shaded plates, two styles of which are shown in the drawings, Figs. 3 and 4.

By differently-shaded plates any degree of shade between white and black can be produced on the negative, thus producing a picture corresponding to the shade on the plate, though it may not be like the plate, for if a plate with parallel lines, as shown in Figs. 3 and 4, is used, the black lines or strips blend 90 with the white and produce a beautiful shade on the negative, and if the plates are shaded in checks or squares another style of shading is produced on the negative, and so on.

By means of the set-screw B and slots in 95 the arm C the frame D, carrying the plate F, can be adjusted to any required inclination to and distance from the lens of the camera.

Having thus described my invention, what I claim, and desire to secure by Letters Patent of the United States, is—

1. In combination with a camera, a device

for vignetting variously shaded negatives while in the camera, consisting of a shaded board or plate graduated from light to dark, held or suspended in front of the lens during exposure, substantially as shown and set forth.

5 2. In combination with a camera and a shaded vignette board or plate, the bifurcated arm C and adjustable suspending device D, provided with a slotted arm K, substantially as set forth.

10 3. In combination with a camera, a remov-

able vignette board or plate with a central opening therein and graduated from light to dark, and adapted to be adjusted between the lens and the object being photographed, substantially as set forth.

15 In testimony whereof I affix my signature in presence of two witnesses.

HAMLIN J. LLOYD.
